UNITED STATES PATENT OFFICE.

FREDERICK F. MEYER, OF PITTSBURG, PENNSYLVANIA.

SELF-LEVELING TABLE.

No. 822,680.

Specification of Letters Patent.

Patented June 5, 1906.

Application filed December 30, 1905. Serial No. 293,897.

To all whom it may concern:

Be it known that I, FREDERICK F. MEYER, a citizen of the United States of America, residing at Pittsburg, in the county of Allegheny and State of Pennsylvania, have invented certain new and useful Improvements in Self-Leveling Tables, of which the following is a specification, reference being had therein to the accompanying drawings.

10 This invention relates to certain new and useful improvements in tables; and the invention has for its primary object the provision of novel means for normally maintaining the table level, whereby should its foundation or support become inclined or tilted the articles supported by said table will not be upset or precipitated.

Another object of this invention is to provide a table which is particularly adapted for steamships or the like vessels, railway-cars, or the like vehicles, and in this connection I have constructed my improved table whereby it will retain its equilibrium irrespective of its foundation or objects surrounding the same.

25 A further object of this invention is to provide a table which will be extremely simple in construction, strong and durable, comparatively inexpensive to manufacture, and highly efficient for the purposes for which it is used.

With the above and other objects in view, which will more readily appear as the nature of the invention is better understood, the same consists in the novel construction, combination, and arrangement of parts to be hereinafter more fully described, and referring to the drawings accompanying this application like numerals of reference designate corresponding parts throughout the several views, in which—

Figure 1 is a side elevation of my improved table. Fig. 2 is a vertical sectional view of the same. Fig. 3 is a bottom plan view of the table. Fig. 4 is a cross-sectional view taken 45 on the line $\alpha\alpha$ of Fig. 1.

To put my invention into practice, I construct my improved table of a table-top 1, a table-top support 2, and depending legs or supports 3. The table-top support comprises two semicylindrical pieces 4 4, having outwardly-extending lugs 5 5, the lugs of one piece being secured to the lugs of the other piece by transverse screw-bolts 6 6. Each semicylindrical piece 4 is formed with a cavity 7, corresponding in contour to the periphery of a spherical body. The lugs 5 5

have their under faces provided with angularly-disposed recesses 8 8, and in said recesses are mounted the upper ends of the legs or supports 3, said upper ends being pierced, as at 9 9, to permit of the screw-bolts 6 passing through said legs. The legs or supports 3 are flanged, as at 10, to further support the pieces 4 4, and said legs are flared outwardly and provided with feet 11 to insure the stability of the table. Between the pieces 4 4 is mounted a spherical body or ball 12, which is retained between the pieces by fitting snugly within the confronting concavities 7 7 of the pieces 4 4. In the spherical body or ball 12 is mounted a standard 14, said standard protruding through the spherical body and corresponding to the axis of said body. The upper end of the standard 14 engages in a socket 15, carried by the underneath face of the table-top 1, a set-screw 16 being mounted in the socket to retain the table-top 1 in engagement with the upper end of the standard 14. The lower end of the standard is threaded, as at 17, and upon this threaded end is mounted a weight 18, adapted to normally retain the standard in a vertical position irrespective of the table-top support 2 and its foundation.

In Fig. 1 of the drawings I have illustrated in dotted lines the table-top support and its foundation as inclined or tilted, and when assuming this position the weight 18 normally retains the standard 14 and the table-top 1 in their original position, this being accomplished through the medium of the spherical ball 12 moving in the concavities 7 7 of the pieces 4 4. In other words, the table-top support 2 moving around the spherical body as its supporting foundation is inclined or tilted, such as would occur aboard a vessel in a rough sea.

I preferably construct my improved table of strong and durable metal, with the exception of the table-top 1, which is preferably constructed of wood, in order to give the table a finished appearance.

By the construction of the table it will be observed that the different parts thereof can be easily and quickly disassembled and placed in a compact form, whereby it will occupy comparatively small space when not being used or in storage.

Such changes in the construction of my improved table as are permissible by the appended claims may be resorted to without departing from the spirit and scope of the invention.

What I claim, and desire to secure by Letters Patent, is—

1. A table of the character described embodying two semicylindrical pieces having 5 concavities formed therein, lugs carried by said pieces, said lugs having recesses formed therein, legs mounted in said recesses, a spherical body mounted in the concavities of said pieces, a standard extending through said 10 body, a table-top detachably connected to said standard, a weight carried by the lower end of said standard, and means to simultaneously hold said legs and said pieces together, substantially as described.
- 15 2. A table of the character described em-

bodying two semicylindrical pieces, legs mounted in said pieces, a spherical body mounted between said pieces, a standard carried by said body, a table-top detachably connected to the upper end of said standard, a weight carried by the lower end of said standard, means to secure said pieces together, and means to secure said legs to said pieces, substantially as described. 20

In testimony whereof I affix my signature 25 in the presence of two witnesses.

FREDERICK F. MEYER.
